CLAIM

The ornamental design for a caulking tube nozzle cutter, as shown and described.

DESCRIPTION

FIG. 1 is a left side elevational view of a caulking tube nozzle cutter showing my new design;

FIG. 2 is a plan view thereof;

FIG. 3 is a right side elevational view thereof;

FIG. 4 is a bottom plan view thereof;

FIG. 5 is a rear elevational view thereof;

FIG. 6 is a front elevational view thereof;

FIG. 7 is a perspective view thereof; and,

FIG. 8 is a perspective view thereof illustrating a cutting blade of my caulking tube nozzle cutter in an extended position.
